A.M.A."

UNITED STATES PATENT OFFICE.

JOHN A. REID, OF FREDERICTON, NEW BRUNSWICK, CANADA, ASSIGNOR TO THE HARTT BOOT AND SHOE COMPANY, LIMITED, OF FREDERICTON, NEW BRUNSWICK, CANADA.

CUSHION-SOLE FOOTWEAR AND METHOD OF MAKING SAME.

1,290,351.

Specification of Letters Patent.

Patented Jan. 7, 1919.

Application filed August 21, 1916. Serial No. 116,102.

To all whom it may concern:

Be it known that I, JOHN A. REID, a subject of the King of Great Britain, and resident of the city of Fredericton, in the Province of New Brunswick and Dominion of Canada, have invented certain new and useful Improvements in Cushion-Sole Footwear and Methods of Making Same, of which the following is a full, clear, and exact description.

This invention relates to improvements in footwear and more especially to that class of footwear having a cushion sole; and to a method of making the same. The object of the invention is to provide an article of footwear having the sole cushion thereof so formed that it extends fully to the edge of the insole in a normal or uncomplicated condition and free from hard ridges such as might be caused by stitching.

A further object is to provide a cushion sole boot or shoe which may be manufactured more readily and cheaply than heretofore.

The invention consists, briefly, in providing an insole split at the edge and skived as usual, a cushion and a cushion cover having flaps which fold down sharply at the edges and are attached under the insole by the welt holding stitches or other suitable means.

The flaps are attached to the cover in such a manner that a hinge is formed at the junction which permits the flaps to assume a position at right angles to the plane of the cover without dragging the edges of the cover and thereby compressing the edges of the cushion. When the parts are assembled the free edges of the flaps are caught by the welt attaching stitches so that the cushion and its cover are secured without the necessity of an additional operation.

In the drawings which illustrate the invention:—

Figure 1 is an enlarged cross-sectional view of a shoe showing the cushion sole in position.

Fig. 2 is a plan view of the cushion sole in position part of the flap stitching being removed.

Fig. 3 is a side elevation of a block used in forming the insole.

Referring more particularly to the drawings, 11 designates the insole of an article of footwear, split at the edge to form upper and lower flaps 12 and 13, respectively, the lower of which is turned inwardly, as shown.

The lower surface of the insole is channeled adjacent the edge, as at 14, for the inseaming operation.

A cushion 15 of suitable material, such as soft wool felt, is provided on the upper side 60 of the insole and is held in place by a cover 16 of soft pliable leather or other suitable material. Flaps 17 are attached to the side edges of the cover and extend from near the toe end to approximately the front end 65 of the heel, as will be clearly seen in Fig. 2. These flaps are preferably of fabric, such as strong tape of suitable width and are connected at an edge to the side edges of the cover by suitable stitching 18 which engages the flaps at the extreme edges so that the flaps lie neither above nor below the edges of the cover but abut the same, so that the edges of the cover are not thickened or hardened by the presence of overlapping 70 tape.

The method of assembling the parts is extremely simple and may be performed most expeditiously. The flaps 17 are first stitched to the cushion cover 16. The cover is then placed upside down on a special block 21 and a cushion 15 superposed and finally the insole 11 is applied with its top surface against the cushion. The three parts are now held in this relation by any suitable means, such as tacking at the toe, heel and shank to the block. The flaps are turned over the edges of the insole and secured temporarily by any suitable means, such as adhesive. These flaps are sufficiently 80 wide to be caught by the stitches 19 which secure the welt 23, upper 24 and insole 11, in position and are therefore laid on the insole in such position that they will be caught. Either before or after the parts are arranged on the block the insole, cushion and cover are stitched together at the toe, as at 20, the stitches passing through all three members.

It will be noted that there are no stitches passing through the members, especially the cushion, at the sides or heel. The result is that the cushion remains in its normal condition, uncomplicated, to the very edge so that no hard ridges are formed at the edges to give discomfort to the wearer's foot as would be the case if the stitches passed through the cushion at the edges. In drawing the flaps over the insole the stitches 18 form a hinge 85 between the flaps and the cover so that the 90

flaps readily assume positions at right angles to the cover without compressing the edges of the cushion. Only sufficient tension is applied to the flaps to make them 5 lie snugly against the edges of the cushion. If desired the cushion may be attached to the insole, except at the heel, by a suitable adhesive. The heel portions of both the cushion and its cover may be entirely free 10 of the insole in order that the cover may be laid forwardly in the lasting operation, thus permitting the heel to be nailed through the insole without the nails passing through the cushion cover.

15 While the flaps have previously been described as of fabric it will be understood that this is not essential as strips of suitable thin and strong leather, or other material, may be used with the same results. In 20 the case of leather flaps the same may be integral with the cushion cover.

The advantages of the construction and method of assembly may be briefly summarized. As regards the product; a cushion 25 is formed which extends clear to the side of the boot or shoe without variation in the degree of cushioning effect, *i. e.*, without the formation of ridges at the edges due to compression of the cushion by stitching.

30 (The compression at the toe by the stitches 20 is not considered as it is entirely out of reach of the wearer's foot). As regards the assembly or making of the articles; outside of placing the various members, which 35 is necessary in any cushion sole structure, the only operations additional to the ordinary operations necessary on any boot or shoe are the attaching of the flaps to the cover the toe stitching 20 and the adaptation 40 of the flaps to the edges of the insole. It will be readily seen that these operations are extremely simple and may be very quickly performed even by unskilled labor

so that the expense thereof may be almost negligible.

The block 21 on which the insole is formed is an important part of the invention. This block is shaped to the curvature the insole will have in the finished article so that the insole is formed to this curvature with the result that when built into the boot or shoe the cover does not wrinkle or fold as it is very liable to do if the insole is formed flat. The blocks are preferably right and left.

What I claim is:—

1. In footwear, the combination with an insole, of a cushion, a cushion cover, flaps at the side edges thereof separate from the cover, stitching hingedly connecting the 60 flaps in edge abutting relation to said cover and stitches passing through said cover, cushion and insole at the toe, the said flaps being positioned on the insole to be caught by the welt attaching stitches and so positioned in relation to the cushion cover that they make a sharp right angular corner therewith when in finished position, substantially as described.

2. A method of making footwear which 70 consists in forming an insole split and channeled on its lower surface, hingedly connecting flaps in edge abutting relation with a cushion cover by means of stitches, superposing a cushion and the cushion cover on 75 the insole, stitching through at the toe, swinging the flaps down and bending them under the insole edges and connecting the cover flaps, welt and upper to the insole by a single stitching operation.

In witness whereof I have hereunto set my hand, in presence of two witnesses.

JOHN A. REID.

Witnesses:

JOHN R. WALKER,
CHAS. F. ROBERTS.
